UNITED STATES PATENT OFFICE

1,928,631

LOCOMOTIVE BOILER HEAD STRUCTURE

Harry M. Pflager, St. Louis, Mo., and William M. Sheehan, Merion, Pa., assignors to General Steel Castings Corporation, Granite City, Ill., a corporation of Delaware

Application February 9, 1931. Serial No. 514,612

2 Claims. (Cl. 122—493)

The invention relates to railway rolling stock and more particularly to the construction of the transverse walls of a boiler located at the rear of the fire-box and at the front ends of the boiler tubes, respectively.

It has been customary to construct the entire boiler shell of boiler plate and to hold the inner and outer walls of the fire-box together by means of staybolts, additional braces being disposed diagonally of the upper front and rear corners of the boiler to prevent bulging and other distortion of the boiler walls because of the high pressure existing in the boiler.

With the increasing pressures being utilized in locomotive boilers, the difficulties of adequately bracing the boiler walls have substantially increased and the main object of the invention is to overcome such difficulties by making all or a substantial portion of the boiler end walls of structures rigid enough to be form sustaining under high pressures and preferably the structures are constructed by casting the same.

A further object of the invention is to eliminate a substantial number of staybolts and the machining and other labor required for fitting and assembling the staybolts with the remainder of the boiler structure.

Another object of the invention is to eliminate a substantial number of joints between overlapped plates, etc. which are difficult to construct and maintain steam tight and water tight.

Another object of the invention is to form suitable mounting elements on the boiler backhead whereby equipment can be secured to the head without the necessity of making openings leading to the interior of the boiler.

Another object of the invention is to form certain structures commonly associated with the backhead integrally with the same to avoid the work of securing separately formed parts together and also to avoid the necessity of frequent inspection and tightening of the structures to the head on which they are mounted.

These and other detail objects of the invention, as it will appear from the description below, are attained by the structure illustrated in the accompanying drawings, in which—

Figure 1 is a longitudinal vertical section through the front and rear portions of a locomotive boiler, the intermediate portion of the boiler being broken away as such portion, in itself, does not form a part of the present invention.

Figure 2 is a vertical transverse section on line 2—2 of Figure 1.

Figure 3 is a rear view of the boiler backhead.

Figure 4 is a similar view showing various apparatus mounted on the backhead.

Figures 5 and 6 are side views of details and are taken on the corresponding lines of Figure 3.

Figures 7, 8 and 9 are vertical sections through 60 the backhead and are taken on the corresponding section lines of Figure 3.

Figure 10 is a bottom view of one rear corner of the structure.

Figure 11 is a vertical transverse section taken 65 on the line 11—11 of Figure 1.

Figure 12 is a top view of the boiler front head and tube sheet and associated structure.

Figures 13, 14, 15 and 16 are detail sections taken on the corresponding section lines of 70 Figure 12.

Figure 17 is a section through the boiler backhead illustrating a modified form of the invention.

Figure 18 is a corresponding section illustrating 75 another form of the invention.

Figure 19 is a rear view of one-half of the boiler backhead shown in Figure 18.

Figure 20 is a bottom view of the same.

Figure 21 is a detail section through a modified 80 form of boiler front head.

Figure 22 is a section taken on the line 22—22 of Figure 21.

Figure 23 is a top view of one-half the boiler front head shown in Figures 21 and 22.

In the preferred form of the invention the boiler backhead 1 and fire-box door sheet 2 comprise a single casting forming a water and steam header. Backhead 1 and fire-box door sheet 2 are braced by vertical ribs 3 provided with openings 4 at intervals to facilitate the circulation 90 of water and steam and for molding purposes.

The lower portions of members 1 and 2 are joined by an integral element 5 which forms a mud ring section and is provided with cored openings 6 through which the core sand may be removed and into which suitable plugs 6^a may be inserted and utilized for cleaning out the mud ring at intervals. A continuous transverse connection 7 between the inner and outer members forms a door 100 opening to the fire-box. Suitable flanges 8, 9, 10 and 11 project lengthwise of the boiler, and the fire-box boiler plate sheets 12 and 13 are secured to these flanges by welding as indicated at W or by rivets as indicated at R.

A horizontal web 14 projects rearwardly from the backhead 1 and, with a flange 15, constitutes a transverse girder reinforcing the upper portion of the backhead. This web is perforated 105 to permit the passage of the staybolts 16 between W and R.

Figure 2 is a vertical transverse section on line 2—2 of Figure 1.

Figure 3 is a rear view of the boiler backhead.

the fire-box crown sheet 13 and the boiler roof sheet 12.

To facilitate the mounting of equipment on the backhead, the latter is provided with suitable 5 pads, brackets, etc. including a pad 17 for mounting the throttle lever 18; pads 19 and 20 for mounting the support 21 for the turret handle rods 22; a pad 23 for mounting the water column 24; a bracket 25 for mounting the duplex air 10 gauge 26 and steam chest pressure gauge 27; pads 28 for wash out plugs 29; a bracket 30 for the feed water heater gauge 31 and steam gauge 32; a bracket 33 for the force feed lubricator 34; brackets 35 for the stoker operating rod 36; a 15 bracket 37 for the stoker steam jet and driving engine gauges 38; a bracket 39 for the brake valve 40; brackets 41 for the power reverse lever 42; a bracket 43 for the automatic brake valve 44; and brackets 45 for mounting the butterfly 20 fire-box door 46.

Suitable transverse elements 47 connect the backhead and fire-box door sheet and cooperate with integral draft rings 48 to provide suitable openings to the interior of the fire-box for the 25 stoker discharge, etc.

Other brackets or pads may be provided as required for different equipment than that shown in Figure 4.

The front boiler head comprises a single main 30 vertical wall 50 with a continuous flange 51 by which it is secured to the boiler sheet 52. The upper portion of the head includes an integral flange 53 forming a socket for receiving the dry pipe 54 and also includes a superheater header 55 35 extending substantially entirely across the front head and forming a reinforcement for the same which eliminates the necessity of a separate reinforcing web corresponding to the web 14 of the backhead and, incidentally, eliminating the necessity 40 for diagonal braces between the front head and the boiler sheet 52. The lower portion of the front head may be machined front and back and the flue holes are either punched or drilled therein so that the flues can be secured 45 to the head in the usual manner.

Preferably the front head is cast in one piece and includes superheater header 55 and a dual throttle valve housing 56.

This projecting structure will include superheated steam passages 57, wet steam passages 58, reinforcing ribs 59 and suitable brackets 60 for mounting the operating cam 61. The side of the smoke box will be depressed as indicated at 62 to provide a mounting for the operating 55 shaft 63 for the throttle and the upper portion of the box will depart from the circular form as indicated at 64 and accommodate the upwardly projecting portions of the superheater header and associated structure.

Figure 17 illustrates a modified structure in which the fire-box door sheet 70 is not cast with the backhead 71 but constitutes a separate boiler plate corresponding to the usual fire-box door sheet. At the door, this plate is curved 65 outwardly to meet the inturned flanges 72 on the backhead and to unite therewith to form the door opening.

70

75

In this structure the ribs between the inner and outer members of the rear header are eliminated and the usual staybolts 73 are utilized.

In the modification shown in Figures 18, 19 and 20, the inner and outer members 74 and 75, respectively, are integral with each other and are braced by a plurality of relatively short horizontal ribs 76 scattered throughout the header. Otherwise this structure corresponds substantially to that shown in Figures 1 and 3, it being understood that the numerous pads and brackets shown in Figure 3 may be included in this and other modifications of the invention. In Figures 21, 22 and 23, there is illustrated a modified front head in which the superheater header is eliminated. The main vertical wall 80 is braced by a web 81 having flanges 82 at its inner end and extending across the head from side to side.

An inwardly extending circular flange 83 serves to mount the dry pipe and bolting flange 84 may be provided along that portion of the top of the head which is so close to flange 83 that there would not be enough room to insert rivets through the inner flange 85.

In all of the forms of the invention, it will be seen that a rigid boiler head structure is provided which is capable of resisting the distortion due to high boiler pressures and which makes possible the formation therewith of additional equipment which heretofore has been manufactured separately and assembled with the heads only by difficult machining and assembling operations.

Obviously many of the elements illustrated and described may be omitted from the structure, if desired, and many of the features may be varied to suit particular conditions and we contemplate the exclusive use of all modifications which come within the scope of the claims.

We claim:

1. In a locomotive boiler, an integral cast structure comprising a back head member having its edges bent over and arranged to form the corners between said member and the boiler wrapper sheet, a fire box rear sheet adjacent the lower portion of said member, ribs connecting said portion and said rear sheet, and a beam-like element on said member above said rear sheet and merging with said edges at opposite sides, said ribs and element bracing said rear sheet and member, whereby said rear sheet and member are of sufficient rigidity to withstand boiler pressures without the use of stays to said wrapper sheet or of other braces.

2. An integral cast boiler structure comprising a front pressure head, the edges thereof being bent over and arranged for attachment to the boiler wrapper sheet, and an elongated hollow steam header member extending across said head and merging with said edges, said header member reinforcing said head whereby the same is sufficiently rigid to withstand boiler pressures without the use of stays to the boiler wrapper or of other braces.

HARRY M. PFLAGER.
WILLIAM M. SHEEHAN.
